ISAAC STROUSE, OF NEW HAVEN, CONNECTICUT.

SPECIFICATION forming part of Design No. 12,689, dated January 10, 1882.

Application filed December 15, 1881. Term of patent 7 years.

To all whom it may concern:

Be it known that I, ISAAC STROUSE, of New Haven, in the county of New Haven and State of Connecticut, have invented a new Design for Corsets; and I do hereby declare the following, when taken in connection with the accompanying drawing and the letters of reference marked thereon, to be a full, clear, and exact description of the same, and which said drawing constitutes 5 o part of this specification, and represents a side view, showing the hip-section complete.

This invention relates to a design for the ornamentation of that part of a corset commonly called the "hip-section"—that is to say, the 15 part of the corset between the front and back, and which extends from under the arm down over the hip; and the design consists in the representation of cords or ribs in series, as shown in the accompanying illustration and 20 hereinafter described.

Transversely across the section, above and below the center, is the representation of a series of ribs, a b, the space between them filled by a series, c, of vertical ribs, the space below the transverse series b filled by two series 25 of ribs, d e, the one running from said transverse series downward and backward, the other from said series d downward and forward, the space above the series a filled by vertical ribs f, as shown in the accompanying illustration. 30

I claim—

The design for the hip-section of a corset, consisting of the transverse series of ribs a b, the space between them filled with vertical ribs c, the space below filled with diagonal series d e, running respectively to the front and rear, the space above filled by vertical ribs f, as shown in the accompanying illustration. 35
